US0D1001107S

(12) **United States Design Patent** (10) **Patent No.:** **US D1,001,107 S**
(45) **Date of Patent:** **** Oct. 10, 2023**

(54) **MICROPHONE**

(71) Applicant: **Shenzhen Xunweijia Technology Development Co., Ltd.**, Shenzhen (CN)

(72) Inventor: **Qibin Mai**, Gaoyao (CN)

(73) Assignee: **Shenzhen Xunweijia Technology Development Co., Ltd.**, Shenzhen (CN)

(**) Term: **15 Years**

(21) Appl. No.: **29/854,824**

(22) Filed: **Sep. 28, 2022**

(51) LOC (14) Cl. **14-01**

(52) U.S. Cl.

USPC **D14/228**

(58) **Field of Classification Search**

USPC D14/341, 343, 345, 349, 356–358, D14/432–434, 238.1, 249, 496–497, 507, D14/135, 137, 159, 163, 167–168, 172, D14/185–186, 191, 193–194, 197, 203.1, D14/203.3–203.4, 204–207, 209.1, 210, D14/212–216, 217, 221, 223–229; D21/324, 333, 513

(57) **CLAIM**

The ornamental design for a microphone, as shown and described.

DESCRIPTION

FIG. 1 is a front perspective view of a microphone, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the microphone, which form no part of the claimed design.
